RUBBER HEEL

Carl F. Stiel, St. Paul, Minn.

Application December 16, 1940, Serial No. 370,333

8 Claims. (Cl. 36—35)

My invention relates to an improvement in rubber heels, of a type designed particularly to be long wearing and wear resistant.

Rubber heels for shoes, boots and the like are extremely common, their resiliency making walking more comfortable and less tiring. While rubber will wear better than most commonly used substances, it is still true that leather heels reinforced with metal plates or hob nails will last much longer and provide a square heel for considerable periods of time. Such metal plates and hob nails, however, are extremely apt to mar surfaces upon which they bear, and make considerable noise.

It is the object of the present invention to provide a rubber heel construction embodying resilient means in the form of spiral nails and the like. These spiral nails have the advantage of reinforcing the rubber, and preventing the rubber from quickly wearing down. At the same time, however, the nails have sufficient spring quality to flex resiliently with the rubber, and accordingly they do not impair the resiliency of the rubber heels. As a result, the heels maintain their shape much longer than would otherwise be possible and at the same time have all of the advantages of the usual rubber heels.

It is a feature of my invention to provide a considerable number of my spiral nails in the body of the heel. Thus as the rubber of the heel is compressed, it packs tightly about the nails, and is supported thereby. Thus, in addition to the advantage of the longer wearing qualities of the exposed nail heads, the rubber itself is pressed harder and firmer.

It is a further feature of my invention to provide on my spiral nails a series of spaced heads which are consecutively exposed as the heel wears. Such a construction is of considerable value, as the spacing of the heads permits the rubber to encase the body of the nail between the spaced heads, and to provide a bearing of rubber for each of the heads as downward pressure on the heel is exerted.

It is important in this construction that as the heel wears down slowly, one head after another will be exposed, thus providing a considerable area of reinforcing at all times exposed while at the same time the body of rubber forming the heel is greater than would be the case if a spiral of the area of the spaced nail heads throughout its entire length were used. In other words, the spaced heads provide a great amount of wearing surface without sacrificing the resiliency of a smaller cross section nail. If a spiral

of the cross sectional area of the heads throughout its length were employed, it would be stiff and relatively inelastic to compression.

It is a feature of my construction that the heel will wear down more evenly than with common constructions of heels, thereby maintaining the upper portion of the shoe in its proper shape. When the heel wears unevenly, the upper portion of the shoe becomes distorted and out of shape. This upper portion of the shoe cannot well be formed back into shape when a new heel is attached to the shoe, and often the shoes have to be discarded while the leather of the upper portion of the shoe is in good condition.

It is a further feature of my invention that the nails will prevent slipping, and provide better traction than common rubber heels. The rubber about the nails prevent the same from marring a surface upon which the heel bears. At the same time, the rubber may be somewhat more resilient than the nails, thus having somewhat the effect of hob nails or cleats, and have the advantages without the common disadvantages of such constructions.

It is a feature of my invention that the spiral nails may be placed at the points of most wear, while the portions of the heel which do not wear as quickly may be left devoid of the reinforcement. This is of assistance in maintaining even wear of the heel surface.

It is a further feature of my invention that the heads of my spiral nails may be irregularly shaped, thus obviating any tendency for the nails to twist or turn in the heel body. The nails may in this way be guarded against any tendency for the spiral to work through the body of the heel upon compression.

These and other objects and novel features of my invention will be more clearly and fully set forth in the following specification and claims.

In the drawing forming a part of my specification:

Figure 1 is a perspective view of a heel embodying a number of reinforcing spiral nails advantageously distributed throughout the body of the heel.

Figure 2 is a greatly enlarged side elevation view of a spiral nail of my new design.

Figure 3 is a top elevation of the spiral nail illustrated in Figure 2.

Figure 4 is a top plan view of a modified form of nail in which the spaced heads are of non-circular shape.

The heel A may be of any desired shape or configuration, and of a size to fit any size of

shoe. The heel A embodies a series of spiral nails, indicated in general by the letter B, placed in advantageous position therein.

The heel A is preferably of resilient material, such as the body 10 of rubber. It may be of any suitable material, however, and the nails B may be successfully used in heels of other materials such as various compositions, imitation leather, compressed leather and the like.

As will be best seen from an examination of Figure 1 of the drawing, the nails B are preferably placed to form an outer row 11 of nails B following the contour of the perimeter of the heel. Spaced within this row 11 of nails I prefer to provide the usual recesses or cavities 12 to accommodate the nails used to attach the heel to the shoe. Between each adjacent pair of recesses 12 I position three consecutive rows of nails B, indicated by the numerals 13, 14 and 15, which, in the case of a heel for a man's shoe, may consist in three nails B in the outer row 13, and two nails in each of the rows 14 and 15. An additional reinforcing nail 16 is placed at each of the forward corners of the heel, to stiffen and strengthen these corners.

The nails B are provided with a spiral shank or body 17 of a cross-sectional area to readily flex or compress when weight is exerted longitudinally thereagainst. Spaced longitudinally of the body 17 I provide a series of spaced heads 19 of relatively larger area, to provide a solid bearing for the weight. The heads 19 are shown circular in shape, but need not be of the specific shape.

In Figure 4 of the drawing, I disclose a nail 35 of a type similar to the nail B, which I have designated by the letter C. The nail C is provided with a spiral body 20, having spaced heads 21 integrally formed therein. The heads 21 are elongated in shape, and prevent any tendency 40 for the nail to twist or turn in the heel body. This form of nail can be readily substituted for the nail B in a manner which will be obvious to those skilled in the art.

In accordance with the patent statutes, I 45 have described the principles of construction and operation of my rubber heel, and while I have endeavored to set forth the best embodiment thereof, I desire to have it understood that obvious changes may be made within the scope of 50 the following claims, without departing from the spirit of my invention.

I claim:

1. A rubber heel comprising a resilient body,

a series of spirals of relatively harder material extending from top to bottom of said body, and a series of longitudinally spaced irregularities in said spirals.

2. A heel comprising a body having top and bottom surfaces, a series of spirals having their axes substantially perpendicular to said surfaces, and a series of irregularities longitudinally spaced in said spirals.

3. A heel comprising a body having top and bottom surfaces, a series of spirals of resilient material relatively harder than said heel body having their axes substantially perpendicular to said surfaces, and spaced irregularities in said spirals.

4. A heel comprising a body having top and bottom surfaces, a series of spirals of resilient material relatively harder than said heel body having their axes substantially perpendicular to said surfaces, and spaced enlargements in said spirals.

5. A heel comprising a body having top and bottom surfaces, a series of spirals of resilient material relatively harder than said heel body having their axes substantially perpendicular to said surfaces, and spaced heads of greater dimensions in at least one direction in said spirals.

6. A heel comprising a body having top and bottom surfaces, a series of spirals of resilient material relatively harder than said heel body having their axes substantially perpendicular to said surfaces, and spaced circular heads of larger diameter than the body of said spirals integrally formed in said spirals.

7. A heel comprising a heel body having opposed top and bottom surfaces, a series of spiral shanks having their axes perpendicular to said surfaces embedded in said body, and spaced heads of irregular shape and of larger cross-sectional area than said spirals integrally formed thereon.

8. A heel comprising a heel body having opposed top and bottom surfaces, a series of spirals of material harder than the material of said heel body having their axes perpendicular to said surfaces and embedded in said body, said spirals being arranged in a border row following the contour of the heel body and closely associated therewith, said heel body having a series of attaching nail recesses therein within said border row, and a series of rows of spirals in said body between each adjacent pair of nail recesses.

CARL F. STIEL.
